[57] CLAIM

The ornamental design for a toy dolphin, as shown.

DESCRIPTION

FIG. 1 is a side elevational view of a toy dolphin showing my new design;

FIG. 2 is a top plan view thereof;

FIG. 3 is a front perspective view thereof;

FIG. 4 is a bottom perspective view thereof;

FIG. 5 is a side perspective view thereof showing the side opposite that shown in FIG. 1; and,

FIG. 6 is a rear perspective view thereof.
